UNITED STATES PATENT OFFICE.

WILLIAM M. GOODWIN, OF CENTRAL SQUARE, NEW YORK.

INTERNAL-COMBUSTION ENGINE.

Application filed January 11, 1927. Serial No. 160,406.

This invention relates to certain improvements in internal combustion engines and refers more particularly to the means for operating the poppet valves which control the 5 fuel intake and exhaust ports including the cam shaft and housing therefor.

The main object is to reduce to a minimum the lost motion in the connections between the cam shaft and poppet valve and thereby 10 to reduce the noise and wear incidental to such lost motion.

One of the specific objects is to run the cam shaft in an oil bath so as to maintain a thin film of oil at the points of contact between the cams and valve actuating parts in 15 contact therewith.

Another specific object is to journal the cam shaft in an oil-containing casing which may be removed or replaced at will with the 20 cam shaft therein so that when replaced the cams will be properly aligned with their respective valves.

A further object is to mount the cam operated tappets or plungers directly upon the oil containing case to be removed or replaced therewith.

Other objects and uses will be brought out in the following description.

In the drawings:

30 Figure 1 is a transverse vertical sectional view of the cam shaft casing and tappet for transmitting motion from the cam to the poppet valve taken in the plane of line 1—1, Figure 2.

35 Figure 2 is a longitudinal sectional view taken in the plane of line 2—2, Figure 1, except that the plunger, cam and cam shaft are shown in elevation.

40 Figure 3 is an enlarged detail sectional view taken in the plane of line 3—3, Figure 2, showing one of the shims for taking up lost motion and the spring clip for holding the same in operative position.

45 In order that the invention may be clearly understood I have shown a relatively small portion of the frame —A— of an internal combustion engine having a circular opening —a— in which is mounted a casing —1— having a cylindrical oil chamber —2— and a radial opening —3— leading from the chamber —2—, said casing being provided with a radial boss —4— through which the opening —3— extends for a purpose presently described.

55 The casing —1— is also provided with one

or more circular flanges —5— eccentric to the axis of the cylindrical chamber —2— so as to extend beyond the outer end of the boss —4— and also beyond the remaining portions of the casing to permit the latter to be 60 inserted or withdrawn endwise into and from the openings —a— in the engine frame —A—.

A cam shaft —6— is provided with a circular flange —7— of substantially the same 65 diameter as the inner diameter of the chamber —2— so as to rotate upon the walls of said chamber as a bearing for the cam shaft —6—.

This cam shaft is also provided with a 70 cam —8— of suitable construction registering with the opening —3— for operating a cylindrical tappet —9— which is guided in the opening —3— and is, therefore, movable radially relatively to the shaft —6—. 75

The tappet —9— is chambered at —10— from its outward end inwardly the greater portion of its length but is closed at its inner end and is also closed at its outer end of a cap section —11— tightly fitted in the adjacent end of the chamber —10—.

This cap section —11— is provided with a central opening for receiving a radially movable tappet section —12— having its outer end enlarged to form a head —13— 85 and its inner end provided with a cross pin —14— to hold the tappet member against outward axial displacement while the head —13— performs a similar function in holding the tappet member against undue inward displacement.

A valve stem —v— is adapted to rest endwise against the outer face of the head —13— of the tappet member —12— and is held in such engagement by the usual spring, not 90 necessary to herein illustrate or describe, it being understood that the valve stem —v— represents an ordinary fuel intake or exhaust valve of an internal combustion engine.

In order to take up any lost motion which 95 may exist in the connection between the tappet —9— and valve —v— or rather between the head —13— of the tappet member —12— and the valve —v— one or more shims —15— may be inserted between the inner face of the head —13— and adjacent outer end face of the cap section —11—, the thickness of the shim being selected according to the amount of lost motion.

That is, shims of different thicknesses are 110

kept on hand to take up the greater part of the lost motion when necessary.

These shims are preferably made in the form of washers having radial slots —16— opening through one side thereof to permit them to be easily and quickly placed in operative position or removed but when placed in operative position are retained by spring clasps —17— constituting split spring rings having their intermediate portions extended across the open ends of the slots —16— and depressed inwardly at —18— to engage the adjacent side of the tappet member —12—, the opposite ends of the clasp being provided with handles —19— by which the clasp may be opened and removed from the washers when necessary to permit the removal of the washer.

A coil spring —20— surrounds the inner end of the tappet member —12— and is interposed between the cross pin —14— and inner end of the cap section —11— for yieldingly holding the head —13— in contact with the outer face of the washer or shim —15— and thereby preventing lost motion between those parts.

The interior of the casing —1— contains a sufficient amount of oil to envelop the cam shaft —6— and cam —8— and also to furnish lubricant for the bearing member —7—, portions of said oil being also conveyed by the rotation of the cam shaft to the periphery of the tappet —9— for lubricating the same in its reciprocatory motion in the guide opening —3—.

Furthermore, this oil is carried in a thin film to the line of contact between the cam —8— and tappet —9— thereby reducing to a minimum the noise and wear incidental to such contact.

It is to be understood, of course, that the cam shaft —6— will be provided with a number of cams —8— corresponding to the number of valves to be operated and that a corresponding number of tappets —9— will be used in connection with their respective cams.

In like manner the number of bearing flanges —7— may correspond approximately to the number of cylinders of the engine.

The casing —1— may also be provided with any number of flanges —5— as may be required to properly support the casing in a corresponding number of openings —a— in the engine frame —A—.

If desired, the casing —1— may be held against rotation in the opening —a— by key screws —a'— which are preferably arranged in the joint between the periphery of the flange —5— and frame —A— as shown in Figure 2.

These screws —a'— may also serve to hold the casing against endwise movement in the frame —a— but when removed the casing —1— with the cam shaft —6— and tappets —9— thereon may be withdrawn endwise

from the frame when desired without disturbing the position of the valve —v—.

It will be noted from the foregoing description that the case or housing with the cam shaft —6— and oil therein may be removed or replaced axially as a unit through the openings —a— in the frame —A— of the engine by simply removing the key —a'— and tappet —9— and that when this unit is placed in operative position its guide opening —3— and boss —4— will extend in the direction of eccentricity of the circular eccentric flanges —5— radial to the axis of the shaft and co-axial with the valve —v— after which the cylindrical tappet —9— may be inserted in the guide opening —3— and one or more shims —15— placed between the head —13— of the tappet section —12— to take up any lost motion between the head —11— of the tappet —9— and adjacent end of the valve stem.

The shims —15— may be inserted between the heads —13— and —11— by simply lifting the tappet member —12— outwardly against the action of its retracting spring —20— and then releasing the member —12— which allows the spring —20— to allow the shims between the heads —13— and —11—.

When the proper shim has been placed in operative position it is retained in that position by the clip —17— shown in Figure 3.

The cylindrical formation of the tappet member —9— permits angular adjustment thereof to permit different portions of its inner flat face to the cam —8—, this adjustment being made by means of the head —11— which extends beyond the outer end of the boss —4— and corresponding end of the tappet —9— and constitutes a convenient handle for that purpose.

Another advantage of the cylindrical form of the tappet —9— is that it may be easily removed and replaced when the valve —v— is removed from its operative position.

What I claim is:

1. In an internal combustion engine of the poppet valve type, an engine frame having an opening, an oil-containing case supported in said opening and removable endwise therefrom and provided with a radial guide-opening, a valve-operating plunger slidably radially in said guide-opening, and a cam-shaft journaled within the oil-containing case for operating said plunger, the opening in the engine frame being sufficiently large to allow the oil-containing case to be withdrawn and replaced endwise therethrough.

2. The combination with an internal combustion-engine frame having a circular opening, a tubular casing supported in said opening and provided with a radial guide opening, a valve-operating plunger movable in said guide opening, and a cam shaft journaled within the tubular casing for operating said plunger, the opening in the frame being of

greater diameter than the external diameter of the casing to permit said casing with the cam-shaft and plunger therein to be displaced endwise without changing the normal 5 relation between the casing, cam-shaft and plunger.

3. An internal combustion engine as in claim 2 in which the circular opening in the

frame is eccentric to the axis of the tubular casing and its longer radius is disposed at 10 the same side of said axis as the guide opening for the plunger.

In witness whereof I have hereunto set my hand this 29th day of December, 1926.

WILLIAM M. GOODWIN.
